UNITED STATES PATENT OFFICE

96,781

DESIGN FOR A CHILD'S GARMENT

Miriam N. Shaffer, Shaker Heights, Ohio

Application January 7, 1935, Serial No. 54,762

Term of patent 14 years

To all whom it may concern:

Be it known that I, Miriam N. Shaffer, a citizen of the United States, residing at Shaker Heights, in the county of Cuyahoga and State of Ohio, have invented a new, original, and ornamental Design for a Child's Garment, of which the following is a specification, reference being had to the accompanying drawing, forming a part thereof, in which

Fig. 1 is a front elevational view showing the garment with the robe part thereof extended, and with the collar sections and wrist straps unfastened.

Fig. 2 is a perspective view showing the garment with the robe part thereof folded, and with the collar sections and wrist straps fastened.

The garment comprises an upper jacket part having sleeves which terminate in mittens, and a robe part, at the front only, which extends below the jacket part. The rear sheet is of a length

corresponding with the length of the jacket part of the garment, while the front sheet is extended below the jacket to provide the robe part.

The lower portion of the robe part may be folded rearwardly beneath the child's feet and the sides of the folded robe part then brought forwardly as shown in Fig. 2. If desired, the robe part may be left in an unfolded condition, such as when the child is in a perambulator, and at which times the robe part may or may not be tucked under.

The collar of the garment comprises two sections, which are connected respectively to the front and rear sheets of the garment, and which may be fastened or buttoned as shown in Fig. 2.

I claim:

The ornamental design for a child's garment substantially as shown and described.

MIRIAM N. SHAFFER.
